MANUALLY OPERATED DRY SHAVER

Barney R. Nyhagen, Bronx, N. Y.

Application September 8, 1938, Serial No. 228,955

3 Claims.

(Cl. 30—43)

This invention relates to hair cutting implements and refers more particularly to an improvement in dry shavers.

The invention broadly comprehends a dry shaver embodying fixed and movable cutter elements having cooperative cutting edges which function to effect shearing of the hair by the pressure and rolling movement of the movable cutter element over the skin.

The invention more particularly resides in a manually operated dry shaver embodying a non-rotary cylindrical inner toothed cutter element and a hollow cylindrical perforated outer cutter element surrounding the non-rotary cutter element and mounted thereon to turn with reference thereto so that the edges of the perforations thereof cooperate with the edges of the teeth of the inner cutter element to shear off the hair which protrudes through the perforations when the outer cutter element is pressed against and rolled over the skin.

As a further feature the invention embodies a dry shaver of the indicated character which is so constructed and arranged as to receive and collect the severed particles of hair interiorly thereof, while permitting of periodic emptying of the same.

The invention further contemplates a manually operable dry shaver which embodies relatively few and simple elements which are capable of economical production and assembly and which is highly efficient for its intended purpose.

With the above enumerated and other objects in view the invention is set forth in greater detail in the following specification, illustrated in the accompanying drawings, and pointed out in the appended claims.

In the drawings:

Fig. 1 is a perspective view of a dry shaver constructed in accordance with the invention.

Fig. 2 is an enlarged sectional view therethrough taken approximately on the line indicated at 2—2 in Fig. 1.

Fig. 3 is an enlarged longitudinal sectional view taken approximately on the line 3—3 of Fig. 2.

Fig. 4 is an enlarged fragmentary perspective view of a modified form of inner cutter element.

Fig. 5 is a fragmentary side view illustrating a modified form of outer cutter element.

Fig. 6 is a perspective view of a dry shaver illustrating a modified form of the invention.

Fig. 7 is an enlarged transverse sectional view

therethrough taken on the line 7—7 of Fig. 6.

Fig. 8 is an enlarged longitudinal sectional view taken on the line 8—8 of Fig. 7.

Referring to the drawings by characters of reference, 10 designates a handle which is provided at one end with a U-shaped bearing yoke 11 having a pair of spaced parallel bearing arms 12 which are formed with aligned slots 13 opening through the outer ends thereof to receive the shank 14 of a bolt having a knurled head 15 at one end and a threaded opposite extremity 16 which receives the knurled nut 17.

An inner non-rotary cutter element, designated generally by the reference character 20, is of hollow cylindrical formation and is formed with longitudinally extending radial slots 21, the opposite extremities of which terminate in slightly spaced relation to the end walls 22. The end walls are provided with outwardly protruding bosses 23 having aligned openings 24 which receive therethrough the bolt shank 14.

The inner cutter element 20 is secured against rotation by tightening the nut 17 to frictionally clamp the bearing arms 12 against the outer ends of the bosses 23. An outer hollow cylindrical cutter element 30 of thin gage metal is mounted in surrounding relation to the inner cutter element with the inner diameter thereof of slightly greater size than the outer diameter of the inner cutter element so that said outer cutter element is capable of free rotation with reference to the inner cutter element. The outer cutter element 30 is of slightly greater length than the main body portion of the inner cutter element but is of lesser length than the distance between the outer end surfaces of the bosses 23 and said outer cutter element has arranged within the opposite ends thereof, the rings or collars 31 which are provided with annular outwardly projecting beads 32, the outer peripheries of which are of slightly greater diameter than the outer cutter element 30 so as to provide a protective means for the opposite end edges thereof.

The collars or rings 31 are frictionally fitted within the outer cutter element 30 and are further retained in place against displacement due to the fact that they are confined between the bearing arms 12. The outer cutter element 30 is formed with annular rows of perforations 33, the edges of which are adapted to cooperate with the edges of the slots 21 of the inner non-rotary cutter element to shear the hair which protrudes through the perforations 33 into the slots 21.

when the outer cutter element is pressed against and rolled over the skin.

In use and operation the device is grasped by the handle and moved backwards and forwards over the skin so that the outer surface of the outer cutter element 30 is caused to roll over the skin. Obviously this causes the hair to protrude into the perforations 33 and into the slots 21 so that the relative rotation of the cutter elements effects a shearing of the hair close to the surface of the skin inasmuch as the gage of the material of the cutter element is extremely thin. The severed particles of hair pass through the slots 21 to the interior of the inner cutter element 20 and are collected therein. In order to permit of periodic emptying or discharge of the severed particles of hair, outlet openings 35 are provided in the ends 22 of the inner cutter element and their discharge may be accomplished by blowing through the openings of one end to force the same through the openings of the other end.

In the modified form of the invention illustrated in Fig. 4 of the drawings, the inner cutter element 20 is provided with angularly or helically disposed slots 21A so that relative movement of the cutting edges of the perforations and slots is at an angle to more effectually shear the hair.

In the modification illustrated in Fig. 5 of the drawings, the endmost perforations 40 of the outer cutter element 30 are in the form of elongated slots having inwardly projecting teeth 41 at the opposite edges thereof. The purpose of this is to provide larger perforations for receiving longer hair that normally could not be accommodated by the smaller perforations 33.

In the modification of the invention illustrated in Figs. 6, 7 and 8 of the drawings, the handle 59 is provided at one end with a U-shaped bearing yoke 51 having a pair of spaced parallel arms 52 and 53, which arms are formed with bifurcated terminals 54 and 55. A bolt 56 is provided having an enlarged head 57 at one end thereof which is fulcrumed on a pivot pin 58 extending transversely through the furcations of the bifurcated terminal 54 of the arm 52. The bolt 56 adjacent the head 57 is provided with a square or non-circular portion 59 while the opposite terminal thereof is threaded as at 60 to receive a knurled nut 61. In this form of the invention an inner non-rotary cutter element 62 is provided, one end portion 63 of which is of semi-spherical formation, the opposite end face 64 thereof being flat. The opposite ends of the inner non-rotary cutter element have protruding therefrom bosses 65 and 66.

The cutter element 62 is provided with an axial bore 67 having an enlarged square or non-circular portion 68 which interfits with the square or non-circular portion 59 of the bolt shank 53 so as to key the cutter element 62 on the bolt against rotation. The threaded extremity 60 of the bolt shank extends through the bifurcated terminal 55 of the arm 53 and tightening of the nut 61 clamps and retains the inner cutter element 62 in operative position with reference to the handle 50. The outer periphery of the cutter element is provided with longitudinally extending grooves 69 which extend partially around the semi-spherical end portion 63.

An outer hollow cylindrical cutter element 70 having a semi-spherical end portion 71 and constructed of a thin gage metal is arranged in surrounding relation to the inner cutter element 62 with the edge of the semi-

spherical end 71 thereof arranged between the enlarged head 57 of the bolt and the semi-spherical end 63 of the inner cutter element.

The outer cutter element 70 is adapted for free rotation with reference to the inner cutter element and the open end edge extends slightly beyond the flat end face 64 of the inner cutter element 62 and has fitted therein a cap 72 formed with a marginal outwardly projecting protecting bead 73. The outer cutter element 70 is formed with annular rows of perforations 74 throughout its length and throughout the semi-spherical end portions 71, the edges of which are adapted to cooperate with the edges of the grooves 69 of the inner non-rotary cutter element 62 to shear the hair which protrudes through the perforations and into the grooves when the outer cutter element is pressed against and rolled over the skin. In this form of the invention, the semi-spherical end portions of the inner and outer cutter elements provide a convex hair shearing medium by virtue of which a close shave may be obtained on any portion of the face or anatomy.

It will also be observed that when it is desired to remove the cutter elements, it is only necessary to remove the nut 61 and swing the bolt on its pivot pin 58 to a position where the cap 72 is first removed, then the inner cutter element 62 and finally the outer cutter element 70. In assembling, this order is reversed.

What is claimed is:

1. A manually operable dry shaver including a handle having a bearing yoke at one end provided with a pair of spaced parallel slotted arms, a bolt extending through the slotted portions of the arms, an inner hollow cylindrical cutter element having protruding bosses at its opposite ends clamped against rotation by said bolt between the arms, longitudinally extending radial slots formed in said cutter element defining cutting teeth, and an outer hollow cylindrical cutter element having perforations providing cutting teeth, said outer cutter element surrounding the inner cutter element and mounted thereon to freely turn with reference thereto for cooperative cutting engagement of the teeth of the inner and outer cutter elements.

2. A manually operable dry shaver including a handle having a bearing yoke at one end provided with a pair of spaced parallel slotted arms, a bolt extending through the slotted portions of the arms, an inner hollow cylindrical cutter element having protruding bosses at its opposite ends clamped against rotation by said bolt between the arms, longitudinally extending radial slots formed in said cutter element defining cutting teeth, an outer hollow cylindrical cutter element having perforations providing cutting teeth, said outer cutter element surrounding the inner cutter element and mounted thereon to freely turn with reference thereto for cooperative cutting engagement of the teeth of the inner and outer cutter elements, and annular collars having beads protruding beyond the periphery of the outer cutter element and fitted against the opposite ends of the outer cutter element to protect the end edges thereof.

3. A manually operable dry shaver including a handle having a bearing yoke at one end provided with a pair of spaced parallel slotted arms, a bolt extending through the slotted portions of the arms, an inner hollow cylindrical cutter element having protruding bosses at its opposite ends clamped against rotation by said bolt be-

tween the arms, longitudinally extending radial slots formed in said cutter element defining cutting teeth, an outer hollow cylindrical cutter element having perforations providing cutting teeth, said outer cutter element surrounding the inner cutter element and mounted thereon to freely turn with reference thereto for cooperative cutting engagement of the teeth of the in-

5 ner and outer cutter elements and annular collars having beads protruding beyond the periphery of the outer cutter element and fitted against the opposite ends of the outer cutter element to protect the end edges thereof, said collars being confined between the arms of said yoke.

BARNEY R. NYHAGEN.
